(57) CLAIM

The ornamental design for a diaper shield, as shown and described.

DESCRIPTION

FIG. 1 is a first perspective view of a diaper shield of my new design;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof; and,

FIG. 8 is a perspective view illustrating the diaper shield in an attached position.

The broken line showing of the diaper shield adhesives are included for the purpose of illustrating portions of the diaper shield that are no part of the claimed design. The broken lines showing of the baby and diaper are included to show environment and form no part of the claim design.

The broken lines shown in the center portion of FIGS. 3 and 8 are included for the purpose of illustrating stitching and are a part of the claimed design.

1 Claim, 6 Drawing Sheets

FIG. 1

FIG. 2

FIG. 3

FIG. 5

FIG. 4

FIG. 6

FIG. 7

FIG. 8
